Des. 223,247
Patented Apr. 4, 1972

223,247

SUCTION CATHETER

David L. Brodsky, Providence, and Elliott J. Brodsky, East Greenwich, R.I., assignors to Superior Plastic Products Co., Providence, R.I.

Filed July 20, 1970, Ser. No. 24,033

Term of patent 14 years

Int. Cl. D24—02

U.S. Cl. D16—1

FIG. 1

FIG. 2

FIG. 3

FIG. 4

FIG. 5

FIG. 1 is a side elevational view of a suction catheter showing our new design;

FIG. 2 is a top plan view thereof;

FIG. 3 is a bottom plan view thereof;

FIG. 4 is an end view looking from the left with respect to FIG. 1; and

FIG. 5 is an end view looking from the right with respect to FIG. 1.

We claim:

The ornamental design for a suction catheter, substantially as shown.
